(57) **CLAIM**

The ornamental design for a locker set for a differential as shown and described.

DESCRIPTION

FIG. 1 is a first perspective view of a locker set for a differential;

FIG. 2 is a second perspective view of the locker set for a differential;

FIG. 3 is a third perspective view of the locker set for a differential;

FIG. 4 is a fourth perspective view of the locker set for a differential;

FIG. 5 represents a front view of the locker set for a differential;

FIG. 6 represents a right side view of the locker set for a differential;

FIG. 7 represents a rear view of the locker set for a differential;

FIG. 8 represents a left side view of the locker set for a differential;

FIG. 9 represents a bottom view of the locker set for a differential;

FIG. 10 represents a top view of the locker set for a differential;

FIG. 11 is a perspective view of a first driver for the locker set for a differential;

FIG. 12 represents a front view of the first driver for the locker set for a differential;

FIG. 13 represents a right side view of the first driver for the locker set for a differential;

FIG. 14 represents a rear view of the first driver for the locker set for a differential;

FIG. 15 represents a left side view of the first driver for the locker set for a differential;

FIG. 16 represents a bottom view of the first driver for the locker set for a differential;

FIG. 17 represents a top view of the first driver for the locker set for a differential;

FIG. 18 is a perspective view of a second driver for the locker set for a differential;

FIG. 19 represents a front view of the second driver for the locker set for a differential;

(Continued)

FIG. 20 represents a right side view of the second driver for the locker set for a differential;
 FIG. 21 represents a rear view of the second driver for the locker set for a differential;
 FIG. 22 represents a left side view of the second driver for the locker set for a differential;
 FIG. 23 represents a top view of the second driver for the locker set for a differential; and,
 FIG. 24 represents a bottom view of the second driver for the locker set for a differential.
